UNITED STATES PATENT OFFICE.

JULIAN O. ELLINGER, OF NEW YORK, N. Y., ASSIGNOR, BY DIRECT AND MESNE ASSIGNMENTS, OF ONE-HALF TO UNIVERSAL ELECTRIC WELDING COMPANY, OF NEW YORK, N. Y., A CORPORATION OF NEW YORK.

ARMOR OR OTHER METAL PLATE.

1,142,241.

Specification of Letters Patent.

Patented June 8, 1915.

Application filed July 15, 1910. Serial No. 572,101.

To all whom it may concern:

Be it known that I, JULIAN O. ELLINGER, a citizen of the United States, and a resident of the city, county, and State of New York, 5 have invented certain new and useful Improvements in Armor or other Metal Plates, of which the following is a specification.

This invention relates to armor plates and means for fastening the same to sides of vessels.

It is now the practice to secure armor plates to the sides of vessels by means of bolts extending into the sides through openings which are drilled through the plates. 15 This practice is expensive, inasmuch as the plates are hardened, by harveyizing them for example so that the drilling of the holes therethrough is a matter of considerable time and labor. It also weakens the plates.

20 The main purpose of the invention is to minimize the expense incident to the attaching of armor plates to the sides of vessels and to overcome the weakness caused by the present mode.

25 This purpose is accomplished by integrally uniting to the comparatively soft backs of the armor plates the bolts which serve to secure said plates to the vessels, and the preferred method of integrally uniting 30 these parts is by electrically welding them together.

The bolts and the backs of the armor plates may be variously prepared for electrical welding, within the spirit of the present invention, the most important requisite being that either or both of the surfaces which are to be weldably united shall be formed to provide for contact with each other a protuberance or portion of reduced 40 cross-sectional area or a portion isolated from the contiguous part, forming portions wherein the heat is localized, so that such portion or portions shall be brought to a welding heat by the current passing there- 45 through before the pressure which is employed to integrally unite the melted molecules brings the bodies of the members being thus united into such intimate contact with each other as to cause a short circuiting 50 of the current and its dissipation, and in the accompanying drawings I have shown a number of various examples of parts prepared so as to embody such requisite.

It is to be understood that these various

forms are to be considered as exemplary and suggestive and that there are many other detail forms which will be quite within the spirit of the present invention and the scope of the subjoined claims. For this reason the invention is not to be construed to be restricted to the particular embodiments herein illustrated and may be embodied in many apparently widely different forms without departing from its spirit or the scope of subjoined claims.

65 In the drawings:—Figure 1 is a view of a section or portion of an armor plate and a portion of a bolt or other fastening element exemplifying a form of the invention wherein each of said parts or members is specially prepared for integral union. Fig. 2 is a similar view wherein the fastening bolt only is specially prepared for such union, illustrating one suitable form of such preparation. Fig. 3 is a similar view wherein the 70 back of the armor plate only is prepared for integral union of the same with the end of the bolt or other fastening element, illustrating one suitable form embodying such preparation. Fig. 4 is a similar view illustrating a preparation of the armor plate only, slightly different from that of Fig. 3. Fig. 5 is a similar view illustrating a preparation of the armor plate only differing 75 slightly from those of Figs. 3 and 4. Fig. 80 6 is another exemplification of the back of an armor plate and the end of a bolt or other fastening element therefor, wherein each is specially prepared. Fig. 7 is a similar view 85 showing a different preparation of both the back of the armor plate and fastening element. Fig. 8 is a view of the form illustrated in Fig. 7, taken from a position at right angles with that of Fig. 7. Fig. 9 is a view intended to illustrate one arrangement 90 of electrodes or terminals which may be employed in the electrical welding process, showing the parts prepared substantially the same as in Fig. 1. Fig. 10 is a view intended to illustrate a different arrangement of electrodes or terminals and embodying a different construction thereof. Fig. 11 is a view similar to Fig. 10, intended to illustrate a preheating step of the 95 process. Fig. 12 is a detail view of an electrode which may be employed. Fig. 13 is a similar view of a modified form thereof. Fig. 14 is a view on a small scale showing 100 105

the armor plate with the bolts rigidly and integrally united thereto.

Referring first to the form shown in Figs. 10 and 11, 20 designates the armor plate and 5 21 the bolt. The rear side of the armor plate is grooved as indicated at 22 to form an isolated welding portion 23, or a series of the same, for union with the end 24 of the bolt or bolts, the latter being shown as a 10 protuberance, inasmuch as the body of the bolt has an annular flange 25 at the base of the end 24. When the parts have been thus prepared, they are suitably connected with terminals of an electric welding machine, of 15 any suitable construction.

The machine itself forms no part of the present invention, and need not be illustrated herein. The terminals, however, are peculiar, and comprise a plurality of elements 20 disposed in contact with the armor plate 20 immediately adjacent to the outer wall of the groove 22. These elements preferably are segments of a split ring, which may be of two parts marked 26 and 27, respectively, in Figs. 11 and 12, or may be made of a greater number of segments, four for example, as shown by the parts marked 28, 29, 30 and 31 in Fig. 13.

The circuit wiring in this embodiment of 30 the invention is such that the elements or segments may be of the same or different polarity and changed from one to the other, for a purpose which will hereinafter appear.

There is another terminal element, marked 35 32 applied to the bolt 21.

In practice, the armor plate and bolt, after 40 having been properly prepared, are connected with the terminals of the welding machine and with the pressure means of the latter. The current is so switched and conducted that it will not pass to the terminal 32, but will flow to the terminals 26 and 27, one of said terminals being of positive polarity and the other negative. The circuit 45 is completed through the isolated portion 23 of the armor plate, as indicated by the arrow in Fig. 11. By this the said portion is pre-heated but it is not brought to a temperature sufficiently high to form a weld. After this 50 pre-heating step is completed, the current is so changed that it will flow to the terminal 32 and also to the terminals 26 and 27, the latter two terminals being now of the same polarity-plus, as shown in Fig. 10 of the 55 drawing. In this step the current passes through the back of the armor plate, through the bolt 21, in the direction of the arrows in Fig. 10. The isolated portion 23 of the armor plate and the end 24 and flange 60 25 of the bolt 21 are brought by the action of the current in this step to a welding heat, whereupon pressure is applied and the soft or plastic metal of these parts is forced together, and the plastic metal of the flange 25 flows and is forced into the groove 22, where-

upon the bolt is integrally united to the back of the armor plate. The preheating of the welding portion 23 while advantageous, is not essential and may be dispensed with, and the whole step of welding may be carried 70 out as shown by Fig. 10.

In Fig. 9 I have also shown where the parts may be united by electric welding without preheating. In this case the terminal marked 33, which is in contact with the armor plate, may be placed on the face thereof, as shown. In this instance the current passes through the terminals 33, through the armor plate 20, through the projection 23 and through the bolt 21, 75 through the terminal 32 back to the welding machine.

It will be understood that in practice the back of each armor plate is provided with a series of bolts and said plates are prepared 80 as described, for attaching the bolts thereto. By attaching the bolts directly to the back of the plate and making them an integral part thereof, the cost of production is reduced to a minimum and the objections 85 caused by providing the plates with openings through which to pass the bolts, as heretofore, are overcome.

In Fig. 1, the armor plate 20 is prepared 90 with a groove 34, quite similar to the groove 22 shown by Figs. 10 and 11, but the bolt 21 has its welding end 35 in the form of a widened head with a convex undersurface.

In Fig. 2 the bolt is substantially the same as in Figs. 9, 10 and 11, and the armor plate 100 20 is formed with a groove, the same as 34 in Fig. 1.

In Fig. 3, the armor plate 20 is formed with a projection 36 which is weldably 105 united to the end of a bolt 21 and has a plane undersurface which does not project laterally beyond the sides of the bolt. The projection 36 extends outward beyond the plane of the body of the plate, and in this form has the same superficial area as the 110 end of the bolt; while in Fig. 4, the same form of bolt 21 is shown. In this case the armor plate 20 has a projection 37 on the rear face thereof with undercut edges 38. The welding surface of this projection is 115 greater than the end of the bolt 21.

In Fig. 5, the bolt 21 is the same as that shown in the prior figure, and in this case it is provided with a projection 39 having a convex outer surface like that shown in 120 Fig. 1.

In the form shown in Fig. 6 the plate 20 has an undercut groove 40 which is formed with welding points 41, and a bolt such as 125 shown by Fig. 1 is provided.

To show that the bolt and the armor plate may be provided with more than one heat localizing portion on each, I have illustrated the construction shown by Figs. 7 and 8. In this form the bolt 21 has a laterally ex- 130

panded end 42 formed with grooves 43 to provide welding projections 44. The plate 20 is similarly grooved at 45 to form the series of projections 46. In this form the bolt is so arranged that its projections 44 will cross the projections 46 on the armor plate. The crossing of the projections forms pockets which communicate with each other and into which the plastic metal of the projections is forced when the bolt is united to the back of the plate by pressure after the projections are brought to the welding temperature.

In all these forms it is to be understood that a terminal of the welding machine is connected to the bolt 21, and the other terminal to the armor plate, and when the current is passed through sufficiently to bring the end of the bolt and the welding points or projections on the back of the armor plate to a welding heat, the two parts are forced together by pressure, whereupon the plastic metal will unite, the projections on one of the elements will be forced in and fill up the recess in the other, and a complete rigid weld is made, the molecules of the metal being united and forming a homogeneous mass. The bolt is thus connected to the back of the armor plate and is an integral homogeneous part thereof.

It is believed that the process for the production of the structure and the advantages thereof, will be understood from the foregoing, and it is further believed that the illustrated forms will be understood to be exemplary merely, and that the invention is not to be construed to be restricted to such illustrated forms and may be embodied in many apparently widely different forms all of which are considered to be within the scope defined by the subjoined claims.

While I have described this invention as applied to armor plate, it is to be understood that plates so made may be used for other purposes on ships than armor plates, and in fact may be used in the manufacture of safes, vaults and other places where thick and heavy plates are necessary.

Having now described my invention, what I claim as new and desire to secure by Letters Patent is:

1. An armor plate, the surfaces of which differ in hardness, provided with fastening elements weldably united to the surface of lesser hardness, the entire structure being homogeneous.

2. A plate of metal, the surfaces of which have a different degree of hardness, series of bolts projecting rearward from the surface which is of lesser hardness and integrally united thereto by electric welds, thereby forming a homogeneous structure.

3. A metal plate the front of which is harder than its back, a fastening element therefor having an end adapted to be weldably united to the back, said end having its portion for union with the back laterally expanded with an extremity of reduced cross sectional area.

4. A metal plate, a fastening element therefor, having an end adapted to be weldably united to the back of said plate, said back being grooved and said end having a flange above the lower extremity of the fastening element.

In witness whereof I have hereunto set my hand at the city, county and State of New York, this 28th day of June, 1910.

JULIAN O. ELLINGER.

In presence of—

AGNES C. O'CONNELL,
ISABEL R. RICHARDS.
